UNITED STATES PATENT OFFICE.

MORTON VAN METER, OF CADILLAC, MICHIGAN.

PLANI-METER.

1,260,486.

Specification of Letters Patent. Patented Mar. 26, 1918.

Application filed August 8, 1917. Serial No. 185,030.

To all whom it may concern:

Be it known that I, MORTON VAN METER, a citizen of the United States, residing at Cadillac, in the county of Wexford and State of Michigan, have invented certain new and useful Improvements in Planimeters, of which the following is a specification.

This invention relates to improvements in planimeters and more particularly to an instrument of the rolling type in which the entire instrument is rolled bodily over the surface of the board and thus can be used to evaluate the area of extended figures, such as cannot be accomplished by the polar type planimeter without resetting.

One of the objects of my invention is to provide a planimeter of sturdy, rugged construction, capable of standing rough usage without injury and in which error due to wearing of its parts under long usage is substantially negligible.

Another object of my invention is to provide such a planimeter which can be manufactured at a comparatively small expense and yet will possess as much, if not greater accuracy than those commonly used.

Another object of my invention is to provide such a planimeter in which no correction of reading is necessary in evaluating large areas as is required in using the polar type planimeter.

Still other and further objects will become readily apparent to those skilled in the art from a consideration of the following description and drawings wherein—

Figure 1 is a plan view of my improved planimeter.

Fig. 2 is a vertical sectional view on the line 2—2 of Fig. 1, and;

Fig. 3 is a transverse vertical sectional view on the line 3—3 of Fig. 1.

In polar planimeters, as for example of the Amsler type, a pair of pivoted arms are provided, the end of one arm being secured to the board surface and the end of the other arm provided with a tracing point for outlining the configuration of the area to be measured. On the latter arm at the rear of the point of connection with the first arm, a record wheel is provided which travels upon the surface of the board and indicates the area included within the outline traced.

One difficulty encountered in using a polar planimeter is in having to account for the area of the zero circle when evaluating large areas and furthermore it will be evident that when used on papers of glazed surface there is always the likelihood of the record wheel giving an erroneous result through slippage in traveling over this smooth surface having but slight tractive engagement with the wheel. In my improved type of planimeter this is eliminated by having the recording wheel travel at all times upon the same surface, namely a conical roller, thus giving a satisfactory and efficient tractive surface. In addition to the above advantage it is possible to evaluate elongated areas, such for example as occur in railroad grade indication drawings, which would require frequent resetting of the polar type planimeter. The roller type planimeter such as I have evolved may be made to travel along a grade line of this character without resetting, giving at the end the desired area reading.

In general the instrument comprises an open frame having front and rear bars 10 and 11 connected at the sides by side pieces 12—12, and 13—13 offset and joined by short bars 14 parallel with the front and back bars.

In the area inclosed within the ends 13, 13, I have mounted a pair of heavy traction wheels 15—15 upon a shaft 16 mounted at its ends in journals 17. These large traction wheels provide the driving mechanism for the planimeter, their motion being transmitted through a gear 18 upon the shaft 16 to the pinion 19 carried upon the end of the cone 20 against which the recording wheel travels. This cone is mounted at its ends in pivot bearings 21, set in brackets 22 secured at the junction of the side members 12 and 14. A shaft 23 parallel with the shaft 16 is positioned between the side members 12, 12, carrying at its center a small wheel 23' which serves as a third point of support for the frame.

The front member 10 is provided with a comparatively wide upper surface 24 with a V-shaped longitudinal groove 25 extending across its front edge portion and upon which the rollers 26 of the carriage indicated in general by the numeral 27 rest. This

carriage 27 is of U-shape having an upper table or surface 28 with opposite depending legs 29, in which are pivoted, as at 30, the ends of the two rollers 26—26 which are of 5 cylindrical form adapted to bear upon the surface 24 and have at their forward ends heads 31 of V-shaped cross section for engagement with the groove 25. This carriage is transversely slidable upon the front bar 10 and is provided at its front leg 29 with an outwardly extending bracket 32 carrying a pointed screw or pointer 33 by means of which the outlines of the figure to be evaluated is outlined. A record wheel carrying 15 frame indicated in general at 34 has a pair of U-shaped arms 35, the ends of which are provided with pivot bearings 36 for engagement with the carriage 27 at opposite ends of the table 28. The U-shaped arms 35 are 20 joined at their base 36 and at the opposite sides thereof extend outwardly forming arms 37 within which the record wheel and its associated mechanism is mounted.

At the ends of the arms 37, 37, pivot 25 bearings 38 are provided in which the record wheel shaft 39 is mounted. The record wheel 40 carried upon the shaft 39 at one end portion thereof registers with a vernier scale 41 and at the other side of its midpoint 30 is provided with a worm 42 engaging with a worm wheel 43 carried on a shaft 44 which extends outwardly at right angles to the shaft 39 and carries on its upper end a counter wheel 46. The length of the bracket 34 is such as to position the record wheel 40 approximately on line with the axis of the cone 20, so that as the carriage 27 travels along the front frame member 10, the record wheel 40 is moved upwardly or downwardly upon the cone according to the movement of the carriage.

In the particular embodiment which I have illustrated the diameter of the driving wheels 15, the reduction of gearing between 45 gear 18 and pinion 19, the pitch of the cone and the diameter of the record wheel are so proportioned and related that the indicating surface of the record wheel is divided into five equal spaces each indicating 50 a square inch. The worm and worm wheel give a reduction of 1 to 20 so that the counter wheel 46 is divided into 10 spaces each equivalent to ten square inches.

In the form illustrated the arrangement 55 of the pivoted yoke in which the record wheel is mounted happens to be such that as it travels from one end to the other of the frame member 10 the point of contact of the indicator wheel with the cone does not 60 follow exactly in a plane including the axis of the conical roller and a slight advancing or retarding of the record wheel is caused as it is moved along the cone independent of any cone rotation. This error, however, 65 it will be noted, is self correcting as any in-

crease in indicated area by movement, for example, to the right in Fig. 1, is on the pointer coming back to its place of start, canceled by the subtraction of the error on the reverse movement of the pointer back 70 to its starting point.

Whereas I have illustrated and described but a single embodiment of my invention it will be evident to those skilled in the art that various changes may be made therein 75 without departing from the spirit of the invention or the scope of the appended claims.

Having described my invention, what I claim is:—

1. A planimeter comprising a frame, a traction wheel, a cone driven by the traction wheel, a carriage slidable on the frame on a line parallel to the axis of the cone, a figure outlining pointer carried by the carriage, and a record wheel movable with the carriage and in engagement with the cone.

2. A planimeter comprising a frame, a pair of spaced apart traction wheels, a cone pivoted in the frame on an axis parallel to the axis of the traction wheels, gears connecting the cone and traction wheels, a member movable on the carriage on a line parallel with the axis of the traction wheels, a pointer carried by the member and a record wheel carried by the member and in engagement with the surface of the cone.

3. A planimeter comprising a frame, a pair of traction wheels, a cone, gears connecting the cone to the traction wheels, a carriage slidable on the frame on a line 100 parallel with the axis of the traction wheels, a record wheel carried by the carriage with its axis of rotation parallel with the axis of the cone and in engagement therewith, and a figure outlining pointer projecting from 105 the carriage.

4. A planimeter comprising a generally rectangular frame, a pair of spaced apart traction wheels journaled within the frame, a cone journaled in the frame, gears connecting the cone and traction wheels, a supporting roller journaled in the frame at a point remote from the traction wheels, a carriage slidable upon the frame on a line parallel with the axis of the traction wheels, 115 a figure outlining pointer thereon, a record wheel for engagement with the cone, and record wheel carrying frame pivotally connected to the carriage.

5. A planimeter comprising a frame, a traction wheel, a cone, gearing connecting the traction wheel and cone, a carriage slidable on the frame on a line parallel with the axis of the cone, a record wheel engaging the upper side of the cone, a record wheel 125 supporting frame, pivoted to the carriage on an axis parallel with the axis of the record wheel, and a pointer carried by the carriage.

6. A planimeter comprising a cone, a 130

frame in which the cone is mounted, means for rotating the cone at a speed rate proportional to the speed rate of frame movement, a carriage slideable upon the frame, on an axis parallel with the axis of the cone, a figure outlining pointer on the carriage, and a record wheel carried by the carriage and in engagement with the surface of the cone.

In testimony whereof I hereunto set my hand in the presence of two subscribing 10 witnesses.

MORTON VAN METER.
